UNITED STATES PATENT OFFICE.

HUGH W. BATCHELLER, OF MARION, INDIANA, ASSIGNOR TO BOJAC MANUFACTURING CO., INC., OF WINOOSKI, VERMONT, A CORPORATION OF VERMONT.

ELECTRICAL SWITCH.

Application filed October 9, 1926. Serial No. 140,528.

This invention relates to electrical switches of the push and pull type, and has for its object to provide a simple and compact switch, operable by a rectilinear movement of a push and pull member.

Of the accompanying drawings forming a part of this specification,—

Figure 1 is a side elevation of a switch embodying the invention.

10 Figure 2 is a section on line 2—2 of Figure 1, showing the circuit broken.

Figure 3 is a view similar to Figure 2, showing the circuit closed.

15 Figure 4 is a section on line 4—4 of Figure 2.

Figure 5 is a section on line 5—5 of Figure 2.

Figure 6 is an end view of the insulating body of the switch.

20 Figure 7 is a section on line 7—7 of Figure 6.

Figure 8 shows separately the fixed terminals of the switch.

25 Figure 9 shows partly in elevation and partly in section the closer shifter hereinafter described.

Figure 10 shows in perspective the resilient jaws of the closer shifter.

30 The same reference characters indicate the same parts in all of the figures.

My improved switch comprises a holder attachable to a support, a pair of terminals 12 fixed to the holder and separated by a gap, the terminals being insulated from each other, preferably by an insulating body portion 13 of the holder. Said body portion shown separately by Figures 6 and 7, is a block of vulcanized fiber, or other rigid insulating material, and is provided with sockets 14 (Figure 7), in which the terminals 12 are fixed, and with a cavity 15.

16 designates a gap-closer of conducting metal, movable in the cavity 15 and guided by the sides thereof. The closer has a circular periphery and is preferably a ball. The cavity 15 has guiding grooves 17 (Figures 4 and 6) in its sides, conforming to opposite portions of the gap-closer 16, and adapted to guide it toward and from the terminals 12.

50 The movement of the closer away from the terminals is limited by a stop 18 which, in this instance, is a pin driven through the body 13, as shown by Figure 5.

The switch includes a manually movable 55 closer shifter, comprising a pair of resilient

hooked jaws 19, connected by a neck 20, the jaws and neck being formed by bending a strip of resilient sheet metal into the form shown by Figure 10, and a push and pull member 21, fixed to the jaws and movable 60 toward and from the terminals 12, in a guide formed, in this instance, by the bore of a tubular metal shank 22, fixed to the body 13, and constituting a portion of the holder.

The jaws 19 are guided by the sides of the cavity 15, and exert a yielding pressure in opposite directions on the circular periphery of the closer 16. The arrangement is such that when the shifter is in the position shown by Figure 2, the jaws act by their closing pressure on the periphery of the closer, to press the latter against the stop 18, and hold it separated from the terminals 12. When the shifter is moved to the position shown by Figure 3, the jaws are first sprung outward 65 by the periphery of the closer, and then spring inward, and act to press the closer against the terminals 12. When the shifter is moving from either of the positions shown by Figures 2 and 3, the jaws are first sprung apart by the periphery of the closer, as indicated by dotted lines in Figure 9, and then spring inward and exert shifting pressure on the closer. As may be seen by comparing Figure 2 with Figure 3, only a slight endwise movement of 70 75 the shifter is required to shift the closer.

The jaws 19 and neck 20 being of conducting metal, I provide an insulating connection between the neck and the member 21, the latter being preferably metallic. Said connection is shown by Figure 9, and comprises an insulating collar 23, formed to enter an orifice 24 in the neck and bear on one side thereof, and an insulating collar 25, bearing on the opposite side of the neck. The collars receive a reduced portion 21^a of the member 21, and are clamped against the neck 20 by the operation of upsetting the portion 21^a to form a bur or head thereon.

The shank 22 is fixed to the insulating body 13, preferably by a head 26, formed on the inner end of the shank and provided with an annular flange 27, which is spun over a shoulder on the body 13, as shown by Figures 2 and 3.

It will be seen that the wear of the closer 16 and jaws 19, caused by the rubbing contact of the jaws with the closer, is very slight, hence the switch is durable.

The shank 22 may be inserted in a hole in 110

a supporting member 28, and secured thereto by a clamping nut 29, engaged with a screw-thread on the shank to press a spring washer 30 against one side of the support and confine the head 26 against the opposite side.

I claim:

1. A switch comprising a holder including a body of insulating material, a pair of gap-separated terminals fixed to the holder, and 10 insulated from each other by said body, a one-piece movable spherical gap closer of conducting material, the body being provided with means for guiding the closer toward and from the terminals, a stop fixed to and 15 insulated by the body and arranged to limit the movement of the closer from the terminals, and a closer shifter comprising a pair of resilient jaws connected by a neck, and a push and pull member, fixed to and insulated 20 from the neck and movable toward and from the terminals in a guide in the holder, the said jaws exerting a yielding pressure in opposite directions on the spherical periph-

ery of the closer, the arrangement being such that when the shifter is moved in one direction, the jaws contract on the closer and press it against the terminals, and when the shifter is moved in the opposite direction, the jaws again contract on the closer and press it against the stop.

2. A switch as specified by claim 1, the insulating body of the holder having sockets in which the terminals are fixed, and a cavity through which the stop extends, so that the terminals are insulated from each other and the stop is insulated from the terminals by said body, the sides of said cavity having grooves formed to guide the gap closer in a predetermined path, and a tubular shank fixed to the insulating body and having means 40 for attachment to a support, the bore of the shank guiding the push and pull member.

In testimony whereof I have affixed my signature.

HUGH W. BATCHELLER.
